TEMPERATURE CONTROL SYSTEM FOR
RAILWAY CARS

Edward A. Russell, Chicago, and Donald W. Miller, Elmhurst, Ill., assignors to Vapor Car Heating Company, Inc., Chicago, Ill., a corporation of New York

Application April 6, 1931, Serial No. 528,058

24 Claims. (Cl. 236—1)

This invention relates to certain new and useful improvements in a temperature control system for railway cars, and more particularly to a system for controlling the car temperature including heating means for raising the temperature within the car when the outside temperature is below normal, and cooling or refrigerating means for lowering the temperature within the car when outside temperatures are above normal.

When prevailing temperatures necessitate the heating of the car, it is desirable that means be provided for automatically maintaining the car at any one of a plurality of selected temperatures, according to the wishes of the occupants of the car when the car is in service, but when the car is out of service, in the interest of economizing on the consumption of heat energy, it is desirable that the temperature within the car be automatically maintained at a certain minimum temperature, that is the temperature should be raised just sufficiently above the outside temperature to prevent injury to the car or its contents. When prevailing outside temperatures make it necessary or desirable to cool the air within the car, it is desirable that means be provided for automatically maintaining the car temperature at a point lower than the outside temperature, but not differing therefrom by too great a difference so that there will be no unpleasant or injurious abrupt change in temperature when entering or leaving the car. When the car is out of service, it is not necessary to cool the car at all and it is desirable that the refrigerating means be thrown entirely out of service. According to the present invention, means are provided for automatically controlling both the refrigerating and heating systems so as to secure the operation and advantages briefly noted hereinabove.

The principal object of this invention is to provide an improved temperature control system for railway cars such as briefly described hereinabove and disclosed more in detail in the specifications which follow.

Another object is to provide an improved refrigerating system for railway cars, provided with means for automatically rendering the refrigerating means ineffective when the car is out of service.

Another object is to provide an improved refrigerating means for railway cars including means for automatically maintaining the car temperature at a predetermined differential from the temperature prevailing outside the car.

Another object is to provide an improved temperature control system for railway cars including

both heating and cooling means, together with a single automatic control mechanism whereby the cooling means is entirely ineffective when the car is out of service, and the heating means is only effective to maintain the car at a certain predetermined minimum temperature.

Other objects and advantages of this invention will be more apparent from the following detailed description of one approved form of apparatus embodying the principles of this invention.

In the accompanying drawings:

Fig. 1 is a diagrammatic plan view of a railway car equipped with the improved temperature control apparatus.

Fig. 2 is a wiring diagram illustrating the control connections between the principal elements of the temperature controlling system.

Referring first more particularly to Fig. 1, A indicates generally a railway car which may be divided into one or more compartments, the car being supported on and movable along the tracks B. The car is here shown as connected in service as a unit of a train, it being the last car in the train and coupled to a preceding car, or the locomotive, indicated at C. On each car is a main steam supply pipe D, having coupling connections D' and D'' at the respective car ends whereby the several supply pipes D on the different cars may be connected together in series to form a continuous steam supply pipe extending from the locomotive throughout the length of the train. Similarly, the air signal line pipe E, and the air brake line pipe F, having connections E' and E'', and F' and F'' at their respective ends, are mounted on each car. Suitable valves are provided at the ends of each train pipe whereby the unconnected ends at the rear end of the train can be closed to maintain the pressure.

When a car is disconnected from a train and is out of service, the air lines E and F are left open and the air pressure in each is dissipated. At such times, in order to supply steam to steam line pipe D whereby the compartments in the car may be heated, one end coupling such as D' may be connected with a similar coupling G' leading from a steam supply pipe G in the train yards. It will be understood that there will be a constant source of electrical energy such as a storage battery on each car, or means may be provided for plugging in power lines from an outside source of supply.

The car is provided with a heating system or apparatus indicated generally at H, and with a cooling or refrigerating system indicated generally at J. A selector switch indicated at K and operated from one of the air lines on the car, in

the present instance the signal line E, automatically controls the operation of both the heating and cooling systems in accordance with whether the car is in or out of service.

- 5 The heating system H may be of the usual vapor type, including a pipe 1 through which steam is delivered from the supply pipe D to and through a vapor regulator 2, to and through a control valve L into the radiators 3 and 4 from 5
 10 which the steam and condensate flow back through valve L to the vapor regulator 2. At X is indicated diagrammatically the electrically operated thermostatic control system for maintaining the car at the desired temperature. If 10
 15 the car is divided into a plurality of separate compartments, there will usually be a complete heating system such as indicated at H (including control system X) for each compartment, each of 15
 20 these systems being duplicates of the one here shown. However, a single selector switch such as indicated at K, and hereinafter described more in detail, suffices for all of the heating systems of 20
 a single car.

The refrigerating or cooling system indicated 25 generally at J may take any of a variety of approved forms. As here shown by way of example it includes a mechanical refrigerating unit 5 driven by an electric motor 6 and supplying refrigerating medium in a refrigerating coil 7 positioned in a cooling chamber 8. The motor-driven fan indicated at 9 forces air through chamber 8 where it is cooled and then delivered through conduit or conduits 10 into the car. It will be apparent that the functioning of the refrigerating system depends upon the operation of motor 6, and a thermostatic control mechanism for the motor 6 is indicated generally at Y, this control mechanism being an important feature of the invention and hereinafter disclosed more in detail. 30
 35 40 The fan motor 9 may, if desired, be coupled up in parallel with motor 6 so that this air circulating fan will be thrown into and out of service simultaneously with the main motor 6. However, it is sometimes desirable to have a separate control for the air circulating motor 9 since it may be desirable to circulate the air for ventilating purposes even though the refrigerating system is not in operation. It will be noted that the thermostatic electric control systems X and Y of 45
 50 55 the heating and refrigerating systems H and J respectively, are both under the control of the single selector switch K which is connected with the air pipe E on the car.

Referring now more particularly to Fig. 2, the 55 electrical connections comprised in and between thermostatic control mechanisms X and Y, and the selector switch K, will be described more in detail. The thermostatic control mechanism X for the heating system H is substantially identical 60 with the system disclosed and claimed in the patents to Parks and Miller, 1,729,519 granted September 24, 1929 and 1,729,748, granted October 1, 1929. This system will only be briefly described here, and reference may be made to the 65 above mentioned patents for a more complete description. The control valve L comprises a casting in which is a rotatable valve part controlled by rock shaft 11 on which is secured the operating lever 12. When the valve is in the position 70 shown in the drawings, steam can flow from the supply into and through the radiators, the steam flowing in from the vapor regulator through pipe 13, thence through valve L and out through pipe 14 to the radiators 3 and 4 from which the 75 steam and condensate return through pipes 15

and 16 to the valve L and thence back through pipe 17 to the vapor regulator, all in well known manner. When lever 12 is thrown over to a corresponding position inclined toward the right at its upper end (Fig. 2) the valve L will be closed 5 and the steam supply to the radiators cut off. The solenoid motor indicated at 18 serves to move lever 12 to the position shown in the drawings, that is moves the valve to "open" position. A corresponding solenoid motor 19 will throw the 10 valve to closed position. A magnet or relay indicated at 20 serves when energized to lift an armature 21 thereby bringing a movable contact 22 into engagement with a fixed contact 23 and completing the circuit through the coil of solenoid 15 18 thereby opening valve L. When relay 20 is de-energized, the armature 21 will drop, bringing movable contact 22 into engagement with a fixed contact 24 thus completing the operating circuit through solenoid 19 and moving the valve to 20 closed position. A circuit breaker indicated generally at 25 and operated by the movement of valve lever 12 serves to break the operating circuits for either solenoid 18 or 19 after the operation of the valve has been completed. 25

A series of controlling thermostats designated as "high", "intermediate", and "low", are indicated at 26, 27, and 28 respectively. The wiring connections are such that any one of these thermostats may be connected in shunt around relay 30 magnet 20 so that when the temperature within the car has risen sufficiently to cause the mercury column in the thermostat to complete a circuit therethrough this shunt circuit will be completed around the magnet 20 so as to deenergize the 35 magnet and permit armature 21 to fall, thus causing a closure of valve L. When the temperature within the car falls below the desired temperature for which the contacts on the thermostat are adjusted, the mercury column will break the shunt 40 circuit through the thermostat whereby magnet 21 is again energized and armature 21 is lifted so as to close the operating circuit through solenoid 18 and again open valve L. At 29 is indicated a manually operable switch whereby any selected 45 one of the thermostats 26, 27 or 28 may be placed in control of the system, or all three thermostats may be thrown out of service, whereby the heating system may be operated to maintain either high, intermediate or low temperatures or entirely thrown out of service. At 30 is indicated a 50 thermally operated switch to break the switch-operating circuits, in case the current flow through one of these circuits persists long enough to heat up the parts and perhaps cause injury to 55 the operating mechanism. The main power lines are shown at 31 and 32, and under normal operating conditions when the car is in service the current for operating the control mechanism X will flow from and to these power lines through the 60 leads 33 and 34. The auxiliary power lines 35 and 36 which extend from selector switch K and lead throughout the several compartments of the car, are connected with control system X through branch leads 37 and 38 respectively. 65

The selector switch K as here shown is of the type disclosed in detail in the Parks and Miller Patent 1,729,748, hereinabove referred to, and claimed in the patent granted February 12, 1929 to Parks and Miller, No. 1,701,761. Briefly described, this selector switch K comprises a Bourdon tube 39 which is connected at 40 with one of the air train pipes, the signal pipe E as shown for example in Fig. 1. When service pressure is present in this air pipe, the Bourdon tube 39 will tend 70 75

to straighten out and will move to the position shown in Fig. 2, whereby through the snap-switch mechanism indicated generally at 41 a movable contact plate 42 will be moved out of engagement 5 with a plurality of fixed contact bars 43, 44 and 45. When the car is out of service and service pressure is absent from the train pipe, the Bourdon tube 39 will tend to contract or curl inwardly so that snap mechanism 41 will move the contact 10 42 into engagement with the several fixed contacts 43, 44 and 45 and electrically bridge the same. When the car is out of service and the contacts in switch K have been closed as just described, current will flow from positive main 31 through wire 46, fixed contact 44, movable contact 42, fixed contact 43, wire 35, wire 37, coil of operating magnet or relay 48, and wires 49 and 34 to the negative main 32. The energization of relay 48 will lift the armature 50 thereby closing a 15 circuit through the low temperature control thermostat 28 and placing this thermostat in control of the system. It will be apparent that the thermostat adjusted for the lowest temperature will control the system regardless of whether or not 20 the intermediate or high thermostats are also operatively connected, since the low thermostat will not permit the temperature within the car to rise materially above the temperature for which this low temperature is set. Therefore, when the car 25 is out of service and the circuit through relay 48 is closed, the low temperature thermostat 28 will be in control of the system to maintain the car temperature at the minimum for which this thermostat is adjusted, regardless of the position in 30 which manual control switch 29 has been left. In case control switch 29 has been left in the "off" position, that is the heating system has been manually thrown entirely out of operation while the car was in service, the operating circuits for 35 the valve-operating solenoids 18 and 19 have been broken through this manual control switch 29. However, it is desirable that the car be maintained at the low or minimum temperature while the car is out of service, even though the system 40 has been entirely thrown out of service by means of manual control switch 29. To accomplish this an auxiliary operating circuit to the solenoids 18 and 19 is completed when the car is out of service and selector switch K is closed, this circuit extending from positive main 31 through wire 46, 45 fixed contact 44, movable contact 42, fixed contact 45, wire 36 and wire 38 to a contact plate 51 with which manual control switch 29 makes contact when moved to the off position.

50 It will now be seen that the heating system may be manually adjusted by means of switch 29 to maintain the car temperature at either the high, intermediate or low temperatures while the car is in service, or the heating system may be entirely thrown out of operation, but when the car is out of service the car is automatically maintained at the low or minimum temperature regardless of the position to which manual switch 29 has been moved. It is sometimes desirable to heat up the 55 car to a higher temperature when out of service, (for example a short time before it is to be put into service) and in order to make it possible to do this an operating button 52 is provided in switch K whereby an insulating block 53 may be moved into engagement with spring contact 43 and move same out of engagement with the movable contact 42 so as to break the circuit through relay magnet 48. Manual switch 29 will then be operated to place either the high or intermediate 60 thermostats in control of the heating system.

In case a plurality of separate car compartments are each provided with a control system X, each compartment may be maintained at a separate selected temperature while in service, but all of the compartments will be automatically maintained at the lower minimum temperature by means of the single selector switch K when the car is out of service. 5

The above heating system and its operations are set forth more in detail and claimed in the Parks and Miller patents referred to hereinabove. According to the present invention, the car A is provided with a separate refrigerating or cooling system J provided with its own thermostatic temperature control mechanism Y, but this cooling 10 system J is also under the control of the selector switch K when the car is out of service. The principal wiring and control connections for the refrigerating system are indicated at the right of Fig. 2 and will now be described. At 54 and 55 15 are shown two electromagnets or relays, the relay 54 being hereinafter referred to as a normally inoperative relay whereas the relay 55 is the normally operative relay. The armature 56 of relay 54 is adapted to fall and make contact with a fixed contact member 57 when relay 54 is deenergized, and in a similar manner the armature 58 of relay 55 makes contact with a fixed member 59 when relay 55 is deenergized. The fixed contact members 57 and 59 are electrically connected 20 as indicated at 60, and when both relays 54 and 55 are deenergized, an operating circuit is completed through the driving motor 6 of the refrigerating system as follows: from positive main 31 through wire 61, manually operative cut-out switch 63, wire 64, motor 6, wire 65, armature 58, fixed contact 59, connector 66, fixed contact 57, armature 56, and wire 66 provided with fuse 67 to the negative main 32. Under normal operating conditions, with the car in service, the relay 54 remains 25 deenergized and the motor circuit is constantly completed through contacts 56 and 57.

At the same time, an operating circuit remains normally closed through the coil of relay 55 as follows: from positive main 31 through wire 61, 30 resistance 68, relay coil 55, resistance 69, wire 69^a, connecting bar 60, fixed contact 57, armature 56, and wire 66 to the negative main 32. A series of similar thermostats designated as "high", "medium", and "low", are indicated at 70, 71 and 35 72 respectively. Each of these thermostats has a low contact member 73, 74 and 75 respectively which are connected in series and makes contact with the mercury column of the thermostat. The thermostat 70 has an upper fixed contact 40 member 73' with which the mercury column 76 makes contact when a certain predetermined high temperature has been reached within the car (where all three thermostats 70, 71 and 72 are positioned). The low temperature thermostat 72 has an upper contact member 75' with which the mercury column may contact at a relatively lower temperature. In a similar manner the medium thermostat 71 has a fixed contact 77 with which the mercury column makes contact at a temperature intermediate the temperatures at which high and low thermostats 70 and 72 become operative. The lower contact members 73, 74 and 75 of the several thermostats are connected by 45 wire 78 with the operating circuit for relay 55 between resistance 69 and the relay coil. The upper contact 73' of high temperature thermostat 70 is connected by wire 79 with the wire 61. It will now be seen that when the temperature 50 within the car is sufficiently high for mercury 75

column 76 of thermostat 70 to make contact with the upper contact member 73' a circuit will be completed through this thermostat as follows: from positive main 31 through wire 61, wire 78, 5 contact 73', mercury column 16, contact 73, wire 78, resistance 69, wire 69^a, contact bar 68, fixed contact 57, armature 58, and wire 66 to the negative main. This circuit is shunted around the coil 55 of the relay so that this relay will become de- 10 energized and permit armature 58 to drop into contact with fixed contact member 59 thus completing the operating circuit for refrigerating motor 6 as already described. When the temperature within the car falls below the predetermined 15 temperature for which thermostat 70 is set, the mercury column 76 will no longer contact with upper contact 73' and this shunt circuit will be broken so that the current will again flow through coil of relay 55, thus energizing this relay and lifting the armature 58 and breaking the motor circuit so that the refrigerating system will cease to operate.

At 80 is indicated a thermostat positioned outside the car, or otherwise located so as to be responsive to temperature conditions existing outside of the car. This thermostat is connected through wire 81 with the lead 61. The movable arm of the thermostat carries a pair of contact members 82 and 83. When the outside temperature is relatively high, the thermostat 80 tends to uncoil or straighten out and the movable contacts 82 and 83 are swung to the right so as to no longer make contact with either of the fixed contact members 84 and 85. Fixed contact 84 is connected through wire 86 with the upper contact 75' of thermostat 72. Fixed contact 85 is connected through wire 87 with the upper contact 77 of intermediate thermostat 71. As the outside temperature becomes lower, the thermostat 80 will tend to coil up so that the lower free end will swing toward the left and bring movable contact 83 into contact with fixed contact member 85. An operating circuit will now be completed through this intermediate thermostat 71 providing the temperature within the car is sufficiently high for the mercury column of this thermostat to make contact with upper contact member 77. Since this upper contact 77 is positioned lower than the upper contact 73' of high temperature thermostat 70, it will be noted that this shunt circuit through intermediate thermostat 71 may be completed even though the operating shunt circuit through high temperature thermostat 70 has been broken. 55 It will also be noted that even though the wiring connections to upper contact 73' of high temperature thermostat 70 are always complete regardless of the outside temperature, the breaking of connections between mercury column 76 and upper contact 73' will have no effect on the system as long as a similar shunt circuit is still complete through the intermediate thermostat 71.

In a similar manner, at a still lower outside temperature, the movable contact 82 will be brought into engagement with fixed contact 84 and a shunt circuit completed through the low temperature thermostat 72. The mercury column of this thermostat will remain in engagement with the upper contact 75' after the temperature within the car has fallen so that the circuit through both high and intermediate thermostats 70 and 71 have both been broken.

It will now be apparent that as long as the 75 temperature within the car is above the tem-

perature for which the controlling thermostat has been adjusted, a shunt circuit will be completed through this thermostat so that relay 55 will be deenergized and the armature 58 will fall so as to complete the operating circuit through motor 6 and the refrigerating system will be put into operation to lower the temperature within the car. When the car temperature falls below the desired temperature, the shunt circuit will be broken at the thermostat, 10 whereupon the relay 55 will again be energized to lift armature 58 and break the motor circuit thereby causing the refrigerating system to cease operating. It is not desirable to have too great a difference between the temperatures existing 15 within the car and the prevailing temperature outside the car, that is the temperature within the car should not be lowered substantially more than a predetermined difference below the outside temperature in order to best provide for the 20 comfort and health of the occupants of the car. Accordingly, the combination of the several inside thermostats 70, 71 and 72, cooperating with the outside thermostat 80 serves to maintain the temperature inside the car at a substantially 25 predetermined difference below the temperature existing outside the car at all times. If the temperature falls sufficiently so that it is not desired to operate the refrigerating system at all, the system may be thrown completely out 30 of operation by opening the switch 63.

It will not usually be desirable or necessary to operate the refrigerating system at all when the car is out of service or no longer connected with a train. The refrigerating system is automatically cut out of service under these conditions by means of the normally inoperative relay 54. The coil of this relay is connected at one side through wire 88 with the auxiliary main 35, and is connected at the other side through wire 89 40 with the lead 66. When the car is out of service and the service pressure is lost in the air line (as already described in connection with the heating system) the selector switch K will cause movable contact 42 to bridge the fixed contacts 43 and 44 so that a circuit through relay 54 will be completed as follows: from positive main 31 through wire 46, contact 44, movable contact 42, fixed contact 43, wire 35, wire 88, coil of relay 54, and wires 89 and 66 to the negative main 32. The relay 54 will now lift armature 56 out of contact with fixed contact member 57 thereby breaking the operating circuit of motor 6. As long as relay 54 is energized, it is impossible to complete the motor circuit regardless of the operation of the several control thermostats and relay 55.

It might be desirable under some circumstances to operate the refrigerating system even though the car is out of service, and this can be accomplished by manually manipulating the button 62 to swing member 53 into engagement with spring contact 43 and move this spring contact out of engagement with contact member 42 whereby the circuit through relay 54 is broken. The refrigerating system can now operate as 65 under normal conditions.

It will now be noted that a complete temperature control system is provided whereby the temperature within the car may be raised and automatically maintained at a desired temperature 70 when prevailing temperature conditions are below normal, and whereby the inside car temperature may be lowered and automatically maintained at a desirable temperature when outside temperature conditions are above normal. When 75

the car is out of service, the refrigerating system is rendered entirely inoperative, and the heating system is only operative to heat the car up to a certain minimum temperature sufficient to prevent injury to the contents of the car. However, means are provided whereby under extraordinary conditions either the heating system or refrigerating system may be used when the car is out of service.

10 We claim:

1. In combination with a railway car, a refrigerating system on the car, a motor for operating the system, a source of power for driving the motor, a plurality of thermostats within the car each adapted to control alternatively at any time the flow of power to the motor so as to maintain a certain temperature within the car, each thermostat being set to maintain a different temperature, and a thermostat responsive to changes in temperature outside the car for determining which of the inside thermostats shall at any given time control the operation of the refrigeration system.

2. In combination with a railway car, a refrigerating system on the car, an electric motor for operating the system, a circuit-breaker adapted to normally break the motor-operating circuit, and a plurality of thermostats within the car each adapted to close a shunt circuit around the circuit-breaker and render same inoperative when a certain maximum temperature is reached in the car, these maximum temperatures being different for each thermostat, and a thermostat responsive to temperature changes outside the car and adapted to selectively close circuits to the several inside thermostats, whereby the temperature maintained within the car by the refrigerating means will automatically vary with changes in the outside temperature.

3. In combination with a railway car, a refrigerating system on the car, a source of power for operating the system, a power supply line on the car which is connected in circuit with a train power source when the car is connected in service as a unit of a train, and means connected with said power line for automatically disconnecting the refrigerating means from its operating source of power when the car is disconnected from the train and the power line is broken.

4. In combination with a railway car, a refrigerating system on the car, a source of power for operating the system, a power supply line on the car which is connected in circuit with a train power source when the car is connected in service as a unit of a train, means connected with said power line for automatically disconnecting the refrigerating means from its operating source of power when the car is disconnected from the train and the power line is broken, and manually operable means for rendering the last mentioned means temporarily inoperative whereby the refrigerating system may be operated in a normal manner when the car is out of service.

5. In combination with a railway car, a refrigerating system on the car, an electric motor for operating said system, a circuit-breaker in the motor operating circuit, a power supply line on the car which is connected in circuit with a train power source when the car is connected in service as a unit of a train, and means connected with said power line for actuating the circuit-breaker when the car is disconnected from the train and the power line is broken.

6. In combination with a railway car, a refrigerating system on the car, an electric motor for operating said system, a circuit-breaker in the motor operating circuit, a pipe on the car which contains air under pressure when the car is connected in service as a unit of a train, and a pressure-operated switch for causing the actuation of the circuit-breaker when the car is out of service and the service pressure in the pipe is absent.

7. In combination with a railway car, a refrigerating system on the car, an electric motor for operating said system, a pair of circuit-breakers in the motor-operating circuit, one circuit-breaker being normally operative to break the motor-circuit and the other circuit-breaker normally inoperative so that the motor circuit is unbroken thereby, thermostatically controlled means for deenergizing the normally operative circuit-breaker whereby the motor circuit is completed when a predetermined maximum temperature is reached in the car, a power supply line on the car which is connected in circuit with a train power source when the car is connected in service as a unit of a train, and means connected with said power line for causing the actuation of the normally inoperative circuit-breaker to break the motor-circuit when the car is out of service and the power-line is broken.

8. In combination with a railway car, a refrigerating system on the car, an electric motor for operating said system, a pair of circuit-breakers in the motor-operating circuit, one circuit-breaker being normally operative to break the motor-circuit and the other circuit-breaker normally inoperative so that the motor circuit is unbroken thereby, thermostatically controlled means for deenergizing the normally operative circuit-breaker whereby the motor circuit is completed when a predetermined maximum temperature is reached in the car, means for varying this maximum temperature in accordance with temperature changes outside the car, a power supply line on the car which is connected in circuit with a train power source when the car is connected in service as a unit of a train, and means connected with said power line for causing the actuation of the normally inoperative circuit-breaker to break the motor-circuit when the car is out of service and the power-line is broken.

9. In combination with a railway car, a refrigerating system on the car, an electric motor for operating said system, a pair of circuit-breakers in the motor-operating circuit, one circuit-breaker being normally operative to break the motor-circuit and the other circuit-breaker normally inoperative so that the motor circuit is unbroken thereby, thermostatically controlled means for deenergizing the normally operative circuit-breaker whereby the motor circuit is completed when a predetermined maximum temperature is reached in the car, a pipe on the car which contains air under pressure when the car is connected in service as a unit of a train, and a pressure-operated means for causing the actuation of the normally inoperative circuit-breaker to break the motor-circuit when the car is out of service and service pressure is absent from the pipe.

10. In combination with a railway car, temperature regulating mechanism thereon including a heating system and a refrigerating system, thermostatic control mechanism for causing the temperature regulating mechanism to maintain a predetermined temperature within the car, a

power supply line on the car which is connected in circuit with a train power source when the car is connected in service as a unit of a train, and means connected with said power line for rendering the refrigerating means entirely inoperative and for limiting the operation of the heating means to the maintenance of a predetermined minimum temperature in the car when the car is out of service and the power line is broken.

11. In combination with a railway car, a temperature regulating mechanism thereon including a heating system and a refrigerating system, thermostatic control mechanism for causing the temperature regulating mechanism to maintain a predetermined temperature within the car, a pipe on the car which contains air under pressure when the car is connected in service as a unit of a train, and a pressure-operated means connected with the pipe and effective when the car is out of service and the service pressure is absent from the pipe for rendering the refrigerating means entirely inoperative and for limiting the operation of the heating means to the maintenance of a predetermined minimum temperature within the car.

12. In combination with a railway car, temperature regulating mechanism thereon including a heating system and a refrigerating system, thermostatic control mechanism for causing the heating system to maintain a predetermined selected temperature within the car, thermostatic control means for causing the refrigerating means to maintain a temperature within the car lower by a substantially predetermined differential than the temperature prevailing outside the car, a power supply line on the car which is connected in circuit with a train power source when the car is connected in service as a unit of a train, and means connected with said power line for rendering the refrigerating means entirely inoperative and for limiting the operation of the heating means to the maintenance of a predetermined minimum temperature in the car when the car is out of service and the power line is broken.

13. In combination with a railway car, temperature regulating mechanism thereon including a heating system and a refrigerating system, thermostatic control mechanism for causing the temperature regulating mechanism to maintain a predetermined temperature within the car, a power supply line on the car which is connected in circuit with a train power source when the car is connected in service as a unit of a train, means connected with said power line for rendering the refrigerating means entirely inoperative and for limiting the operation of the heating means to the maintenance of a predetermined minimum temperature in the car when the car is out of service and the power line is broken, and manually operable means for rendering the last mentioned means temporarily inoperative.

14. In combination with a railway car, temperature regulating mechanism thereon including a heating system and a refrigerating system, thermostatic control mechanism for causing the heating system to maintain a predetermined selected temperature within the car, thermostatic control means for causing the refrigerating means to maintain a temperature within the car lower by a substantially predetermined differential than the temperature prevailing outside the car, a power supply line on the car which is connected

in circuit with a train power source when the car is connected in series as a unit of a train, auxiliary means for automatically setting the first mentioned thermostatic control mechanism for limiting the operation of the heating means to the maintenance of a predetermined minimum temperature in the car, auxiliary means for rendering the refrigerating means temporarily inoperative, and a means operatively connected with the power supply line and with the auxiliary means to cause these means to operate when the car is out of service and the power line is broken.

15. In combination with a railway car, temperature regulating mechanism thereon including a heating system and a refrigerating system, thermostatic control mechanism for causing the heating system to maintain a predetermined selected temperature within the car, thermostatic control means for causing the refrigerating means to maintain a temperature within the car lower by a substantially predetermined differential than the temperature prevailing outside the car, a pipe on the car which contains air under pressure when the car is connected in service as a unit of a train, auxiliary means for automatically setting the first mentioned thermostatic control mechanism for limiting the operation of the heating means to the maintenance of a predetermined minimum temperature in the car, auxiliary means for rendering the refrigerating means temporarily inoperative, and a pressure operated means connected with the pipe and with the two auxiliary means to cause these auxiliary means to operate when service pressure is absent from the pipe.

16. In combination with a railway car, temperature regulating mechanism thereon including a heating system and a refrigerating system, thermostatic control mechanism for causing the temperature regulating mechanism to maintain a predetermined temperature within the car, auxiliary control mechanism for rendering the refrigerating means temporarily inoperative, auxiliary control mechanism for limiting the operation of the heating means to the maintenance of a predetermined minimum temperature in the car, a power supply line on the car which is connected in circuit with a train power source when the car is connected in service as a unit of a train, and means connected with and actuated from the power line for causing the two auxiliary control mechanisms to operate when the car is out of service and the power line is broken.

17. In combination with a railway car, temperature regulating mechanism thereon including a heating system and a refrigerating system, thermostatic control mechanism for causing the temperature regulating mechanism to maintain a predetermined temperature within the car, auxiliary control mechanism for rendering the refrigerating means temporarily inoperative, auxiliary control mechanism for limiting the operation of the heating means to the maintenance of a predetermined minimum temperature in the car, a pipe on the car which contains air under pressure when the car is connected in service as a unit of a train, and a pressure operated means connected with the pipe and with the two auxiliary control mechanisms to cause these auxiliary control mechanisms to operate when service pressure is absent from the pipe.

18. In combination with a railway car, temperature regulating mechanism thereon including a heating system and a refrigerating system, thermostatic control mechanism for causing the temperature regulating mechanism to maintain a

predetermined temperature within the car, auxiliary control mechanism for rendering the refrigerating means temporarily inoperative, auxiliary control mechanism for limiting the operation of 5 the heating means to the maintenance of a predetermined minimum temperature in the car, a pipe on the car which contains air under pressure when the car is connected in service as a unit of a train, and a pressure operated means connected 10 with the pipe and with the two auxiliary control mechanisms to cause these auxiliary control mechanisms to operate when service pressure is absent from the pipe, and manually operable means for rendering the pressure operated means 15 temporarily inoperative.

19. Apparatus for regulating the temperature within an enclosure, comprising a refrigerating system, control mechanism comprising a plurality of thermostats within the enclosure adapted 20 to selectively control at any time the refrigerating system, each thermostat functioning to maintain a different predetermined temperature within the enclosure, said control mechanism also including thermostatic means positioned outside the enclosure 25 for selecting the inside thermostat that shall be effective at any given time so that a selected inside temperature will be maintained throughout a predetermined range of outside temperatures, the inside temperature being different for each successive outside temperature range.

20. Apparatus for regulating the temperature within an enclosure, comprising a refrigerating system, a motor for operating the system, a source of power for driving the motor, a plurality of 35 thermostats within the enclosure each adapted to control alternatively at any time the flow of power to the motor so as to maintain a predetermined temperature within the enclosure, each thermostat being set to maintain a different predetermined temperature, and thermostatic means 40 positioned outside the enclosure for determining which inside thermostat shall control the refrigerating system at any given time.

21. In combination with heat-exchange apparatus for maintaining a desired temperature 45 within a space, regulating means for automatically controlling the action of the heat-exchange apparatus to maintain a selected space temperature, said means comprising a plurality of thermostats positioned within the space and progressively and separately operative at different predetermined space temperatures, and thermo-

static means positioned outside the space and functioning at different outside predetermined temperatures to determine the inside thermostat which shall control the space temperature for each outside temperature range between the 5 predetermined outside temperatures.

22. In combination with heat-exchange apparatus for maintaining desired temperatures within a space, regulating means for automatically controlling the action of the heat-exchange apparatus to maintain selected space temperatures dependent upon outside temperatures comprising a plurality of thermostats positioned within said space which operate to maintain said space at different definite temperatures according to which of said thermostats is in control of the heat-exchange apparatus, and thermostatic means located outside of said space which operates at the limits of different ranges of outside temperature to select and put in control 20 of said heat-exchange apparatus a different inside thermostat for each outside temperature range.

23. In combination with heat-exchange apparatus for maintaining a selected temperature 25 within an enclosure, regulating means for controlling the action of the heat-exchange apparatus to maintain any selected one of a plurality of temperatures within the enclosure, said means comprising a plurality of thermostats, 30 each thermostat adapted to function to maintain a certain predetermined one of these temperatures, and thermostatic means responsive to outside temperatures for selecting the temperature to be maintained within the enclosure. 35

24. In combination with heat-exchange apparatus for maintaining a selected temperature within an enclosure, regulating means for controlling the action of the heat-exchange apparatus to maintain any selected one of a plurality 40 of temperatures within the enclosure, said means comprising a plurality of thermostats, each thermostat adapted to function to maintain a certain predetermined one of these temperatures, and thermostatic means responsive to outside 45 temperatures for selecting the one of the first-mentioned thermostats which shall control the inside temperature for each prevailing outside temperature.

EDWARD A. RUSSELL. 50
DONALD W. MILLER.

CERTIFICATE OF CORRECTION.

Patent No. 2,102,225.

December 14, 1937.

EDWARD A. RUSSELL, ET AL.

It is hereby certified that error appears in the printed specification of the above numbered patent requiring correction as follows: Page 6, second column, line 2, claim 14, for the word "series" read service; and that the said Letters Patent should be read with this correction therein that the same may conform to the record of the case in the Patent Office.

Signed and sealed this 22nd day of February, A. D. 1938.
